UNITED STATES PATENT OFFICE.

WILLIAM DOUGLAS WOODRUFF, OF BELTON, TEXAS.

CRATE.

1,347,923.

Specification of Letters Patent. Patented July 27, 1920.

Application filed February 11, 1920. Serial No. 357,945.

To all whom it may concern:

Be it known that I, WILLIAM DOUGLAS WOODRUFF, a citizen of the United States, and a resident of Belton, in the county of 5 Bell and State of Texas, have invented certain new and useful Improvements in Crates, of which the following is a specification.

My invention is an improvement in 10 crates, and has for its object to provide a device of the character specified especially adapted for carrying fruit, as, for instance, peaches, tomatoes, berries and the like, and for retaining said fruit in perfect condition, without bruising or mashing, and 15 which may be stacked one upon the other without danger of collapsing.

In the drawings:

Figure 1 is a perspective view of the improved crate, with one of the trays removed;

Fig. 2 is a perspective view of the removable end;

Fig. 3 is a front view of a portion of the 25 crate, with the end removed;

Fig. 4 is a partial side view.

In the present embodiment of the invention the improved crate consists of a bottom plate 1 and a top plate 2, the said plates 30 being of wood or the like, and the said plates are connected by vertical plates 3 of equal length, the said plates 3 being arranged in series, one series at each side of the crate. The plates 3 connect the top and 35 bottom and also space the top and bottom, and they are spaced apart from each other a sufficient distance to provide free ventilation.

Guide bars or cleats 4, 5 and 6 are 40 surely connected with the plates 3, a series of cleats or guide bars 4, 5 and 6 being connected with each series of plates 3, and these guide bars or cleats are spaced apart from each other, the guide bars 4 being secured 45 to the plates 3 at the bottom plate 1, the cleat or bar 6 being secured to the plates 3 at the top 2, while the cleat 5 is secured to the plates 3 intermediate the top and bottom.

50 Referring to Fig. 4 it will be seen that the top 2 and the bottom 1 extend beyond the plates 3 at each end of the crate and at one end each of these top and bottom plates has a transverse cleat 7. These cleats 7 55 are spaced apart far enough from the adjacent edges of the adjacent plates 3 to per-

mit the insertion of an end 8, the said end being slipped between the cleats 7 and the side plates 3, and the end 8 may be held in position in any suitable or desired manner, 60 as, for instance, by nails or screws.

A series of trays is arranged between the guide bars 4 and 5 and another series between the guide bars 5 and 6, all of the 65 said trays being similar. Each tray consists of a frame formed from substantially parallel side members 9 and connecting end members 10 rigidly secured to the ends of the side members, cross plates 11 being secured to one face of the frame, and extending 70 between the side plates and being secured in place in any suitable or desired manner, and these plates 10 are spaced apart from each other a sufficient distance to 75 secure ventilation, without permitting the fruit to fall through.

The side and end members 9-10 of the frame are of such width that the completed 80 crate will just fit between the guide bars 4 and 5 and between the guide bars 5 and 6, and the crates as a whole are of such 85 length that they will move easily between the series of connecting plates 3 which connect the top 2 and bottom 1. The trays are also of such width with respect to the 90 crate that two trays may be inserted side by side in each pair of guideways. At that end of the crate remote from the end 8 a cleat 12 is secured transversely of the upper 95 face of the bottom, and a door 13 is adapted to be inserted between the cleat and the vertical plates 3. This door 13 is provided on its inner face at each end with a transverse strip or cleat 14 and it is provided on its outer face at its top edge with a 100 transverse strip or cleat 15. The cleats 14 engage outside of the adjacent plates 3 when the door is in place, and the cleat 15 bears against the under face of the top. The cleat and the top are provided with 105 openings 16 which are adapted to register when the door is in place to receive pins, screws or the like to hold the door in place.

Referring to Fig. 1, it will be seen that each tray has the upper edge of its ends cut 110 away, as shown at 17, to provide handholds for convenience in handling the tray.

A crate constructed as specified and carrying trays in which the fruit is held is thoroughly ventilated so that there is no 115 danger of spoiling of the fruit, while at the same time the fruit is not easily removed by

unauthorized parties. A seal may be passed through the opening 16, if desired, thus providing a check for preventing opening of the crate. The fruit is visible so that its 5 condition may be noted, and it is so held that it cannot be injured by pressure. Each layer of fruit is separate, the trays being of a size to contain a single layer of oranges, peaches or like fruit.

10 I claim:

1. A crate of the character specified consisting of a top and a bottom plate, and strips spaced apart from each other connecting the top and the bottom plates, said 15 top and bottom plates being extended beyond the strips at their ends, an end plate arranged between the top and bottom at one end, and a removable end at the other end, said removable end comprising a plate 20 adapted to rest at its lower edge on the bottom, the bottom having a cleat fitting outside of the end and said end having cleats engaging outside of the side strips when the end is in place, a strip arranged transversely 25 of the top of the end on the outer face, said strip and the top having openings for receiving fastening means, and the crate having upper and lower series of guides for receiving trays, and trays on the guides.
- 30 2. A crate of the character specified consisting of a top and a bottom plate, and strips spaced apart from each other connecting the top and the bottom plates, said top

and bottom plates being extended beyond the strips at their ends, an end plate arranged between the top and bottom at one end, and a removable end at the other end, said removable end comprising a plate adapted to rest at its lower edge on the bottom, the bottom having a cleat fitting outside of 40 the end and said end having cleats engaging outside of the side strips when the end is in place, and a strip arranged transversely of the top of the end on the outer face, said strip and the top having openings for receiving fastening means, and the crate having upper and lower series of guides for receiving trays.

3. A crate of the character specified consisting of a top and a bottom plate, and strips spaced apart from each other connecting the top and the bottom plates, said top and bottom plates being extended beyond the strips at their ends, an end plate arranged between the top and bottom at one end, and a removable end at the other end, said removable end comprising a plate adapted to rest at its lower edge on the bottom, the bottom having a cleat fitting outside of the end and said end having cleats engaging outside of the side strips when the end is in place, and a strip arranged transversely of the top of the end on the outer face, said strip and the top having openings for receiving fastening means.

WILLIAM DOUGLAS WOODRUFF.
